UNITED STATES PATENT OFFICE.

HENRY RICHARDSON, OF CHICAGO, ILLINOIS.

WIRE FABRIC.

1,098,686.

Specification of Letters Patent.

Patented June 2, 1914.

Application filed February 7, 1913. Serial No. 746,807.

To all whom it may concern:

Be it known that I, HENRY RICHARDSON, a subject of the King of Great Britain, residing at Chicago, in the county of Cook and State of Illinois, have invented certain new and useful Improvements in Wire Fabrics, of which the following is a specification.

This invention relates to wire fabrics, and 10 has reference more particularly to wire fabrics of the kind at present extensively used to form the bottoms of beds, couches and like articles of furniture.

One type of bed and couch fabric now 15 widely employed is characterized structurally by the use of parallel longitudinal strands of interhooked bent wire units or links, connected transversely at intervals by wire cross links. The weakest point in this 20 type of fabric resides in the hooks by which the longitudinal units or links are connected up end to end. The stretching strains imposed on the longitudinal strands in service tend to pull or straighten out the free end 25 portions of these hooks, and the capacity of the latter to resist these tension strains is very far below the tensional resistance capacity of the body portions of the units themselves. This necessitates the employment 30 of a much heavier and stiffer wire than would otherwise be necessary.

A leading object of my present invention is to provide a construction that will permit the use of a much lighter wire than has 35 heretofore been possible or practicable in wire fabrics of this type, thereby reducing both the weight and the cost.

Another object of the invention, ancillary to the main object above stated, is to provide 40 an improved construction of that type which dispenses with the use of separate cross links between the adjacent longitudinal strands, while preserving both the longitudinally and transversely foldable character of the fabric. 45 This object I accomplish by means of a unit having a cross-arm consisting of an integral extension of one side of a crossed-wire loop formed at one end of the two-ply tension member of the unit of the structure and providing 50 the free end of said extension with a hook that connects with a laterally adjacent strand of the fabric, the units being so assembled and interconnected as to avoid the presence anywhere in the longitudinal strands of the fabric of the open hooks or

loops that are liable to pull out when the fabric is subjected to lengthwise strain.

With these objects in view, my invention resides in the novel fabric structure, and in the novel bent wire unit forming the basis 60 thereof, substantially as hereinafter described and definitely pointed out in the claims.

A fabric representing the best embodiment of the principle of my invention which 65 I have thus far devised is illustrated in two slightly differing forms in the accompanying drawings, in which—

Figure 1 is a plan view of a portion of a bed bottom frame equipped with one form 70 of my improved wire fabric, the latter being broken out between its ends; Fig. 2 is an edge view of Fig. 1, with the end bars of the frame appearing in cross-section; Fig. 3 is a perspective detail elevation of the bent wire 75 member forming the base or unit of the fabric shown in Figs. 1 and 2; Fig. 4 is a fragmentary perspective detail illustrating the formation at one edge of the complete fabric; Figs. 5, 6, 7 and 8 are views corresponding with Figs. 1, 2, 3 and 4, respectively, and illustrating a slightly varied form of the fabric of Figs. 1 to 4 embodying 80 the broad principle of the invention.

Referring to the drawings, 10 may designate one of the longitudinal bars of the bed frame, and 11 and 12 the end cross bars, united to the longitudinal bars by rivets 13. The end bars 11 and 12 have upstanding flanges apertured as usual for the reception 90 of the end hooks of the usual helical springs 14 and 15, through which the ends of the bed bottom fabric are commonly united with the cross bars of the frame to furnish the desired resiliency and elasticity. 95

Referring now to the fabric itself, this is made up (except as to one longitudinal end thereof), of bent wire units interlooped end to end to form longitudinal strands, each of said units comprising a two-ply tension 100 member having one closed end and a two-ply crossed-wire loop at the other end for engagement with the two-ply crossed-wire loop and closed end, respectively, of longitudinally adjacent units, and an integral 105 cross arm formed as an extension of one member of the two-ply crossed-wire loop and terminating in a hook connected to an adjacent longitudinal strand.

Considering now more in detail the form 110

of the invention shown in Figs. 1 to 4, inclusive, 16 and 17 designate straight, substantially parallel lengths of wire constituting the two limbs of a two-ply tension member forming the main body portion of the unit, and connected at one end by a U-bend 18 serving both as a cross-connection for the limbs 16 and 17 and as a unit connecting loop. At the other end of the member 10 16 the wire is bent downwardly and thence upwardly across itself forming one member 19 of a pair of closed loops at this end of the tension member, the wire extending thence above and across the limb 16 of the 15 tension member in the form of a cross-arm 20, which terminates at its outer or free end in a downwardly bent snap hook 21. At the same end of the member 17 the wire is similarly bent downwardly and thence upwardly across itself, forming the other member 22 of the pair of closed loops, the wire extending thence in the form of a horizontally disposed, laterally projecting loop 23, the free end of which is clenched beneath the 20 25 the tension member 17. It will be noted that in the construction described the cross-arm 20 constitutes an extension of the loop 19, springing from between the limbs 16 and 17 of the tension member, and also lying 30 between the inner ends of the arms of the lateral loop 23. It will also be noted that the said loop 23 constitutes an extension of the loop 22 and likewise springs from between the limbs 16 and 17 of the tension 35 member and is disposed directly opposite to the cross-arm 20.

In the preferred method of connecting up the units as shown in the drawings, U-bends 18 of one end row of units are engaged by 40 the hooks of the adjacent row of helical springs, and the loops 19 and 22 of the other end row of units are likewise engaged with the hooks of the adjacent row of helical springs. Between the end rows, the U-bends 45 18 of each transverse row are interlooped with the loops 19, 22 of the next adjacent transverse row of units. The hooks 21 of each longitudinal row of units are engaged with the lateral loops 23 of an adjacent longitudinal row. At one longitudinal edge of 50 the fabric (which would be the right-hand edge as shown in the drawings) the hooks 21 and the greater portion of the cross-arms 20 are omitted, only sufficient length of 55 cross-arm wire being retained to bend or fold beneath the limb 16 of the tension member, as shown at 24 in Fig. 4; this construction being adopted in order to effect a neat finish at the edge of the fabric.

60 It will be observed that the described construction entirely dispenses with open hooks or loops as a means of uniting the units end to end, while at the same time fully preserving the foldable character of the fabric both 65 lengthwise and crosswise at the several

points at which the units are interlooped and interhooked.

By reason of the fact that the cross-arms 20 and laterally projecting loops 23 spring from between the limbs 16 and 17 of the main tension member, these limbs exert in a measure a clamping or gripping action upon the wire at these points, tending to prevent any contracting or pulling out of the loops.

75 Referring to the varied form of the invention illustrated in Figs. 5 to 8, inclusive, of the drawings, the difference between this form and that already described resides in the fact that the horizontally disposed, laterally projecting loop 23' of the unit is formed as an extension of the vertically disposed closed loop 19', and extends across both limbs 16' and 17' of the tension member, its free end being clenched beneath the 80 limb 16'; and, similarly, the cross-arm 20' is formed as an extension of the closed loop 22', passing upwardly through the lateral loop 23' and thence laterally between the arms of the latter and across both limbs 16' and 17' of the tension member. In this construction, the cross tension on the fabric when under load obviously tends to draw the limbs 16' and 17' of the tension members closely together at their lower ends. 85 It will further be noted that in both forms of the invention shown and described the wire of each limb of the tension member, after it has formed the loop 19 or 22 (or 19' or 22') is brought up and thence across 90 100 itself; that is to say, the two ends of the wire forming the two-ply terminal loop are brought back from the extremity of the unit a distance equal to the length of the loop, whence one end is extended to form a cross-arm, and the other is securely clenched to the tension member. This construction is of great importance, since it securely fastens the loops of the fabric at the juncture points of the longitudinal and transverse 105 members of the unit, thereby effectively preventing any pulling-out or distortion of the terminal loops under strain, as well as obviating stretching of the transverse connections. The fabric of my invention also entirely obviates the presence in the line of 110 lengthwise strain of any hooks having free ends, and thereby makes feasible the use in the fabric of a much lighter gage of wire than has ever before been practicable in the 115 wire link fabrics of this general class.

120 It will be manifest to those skilled in the art that the two forms of the invention herein shown and described do not necessarily exhaust the possible embodiments of 125 the principle involved therein, but that they may be modified in detail as individual taste or judgment may dictate without involving any departure from the substantial principle of the structure or sacrificing of 130

the advantages and benefits attained thereby. Hence I do not limit the invention exclusively to the forms herein shown, except to the extent clearly indicated in specific 5 claims.

I claim—

1. A wire link fabric made up of integral bent wire units arranged in longitudinal and transverse rows, each of said units 10 comprising a two-ply tension member the two limbs of which are joined at one end forming a closed end for the unit, a pair of crossed-wire loops at the other end of said tension member, and a laterally extending 15 cross-arm on one side of said tension member; the units of the longitudinal rows having their proximate closed ends and crossed-wire loops connected, and the units of the transverse rows being connected through 20 said cross-arms.

2. A wire link fabric made up of integral bent wire units arranged in longitudinal and transverse rows, each of said units comprising a two-ply tension member the two 25 limbs of which are joined at one end forming a closed end for the unit, a pair of loops at the other end of said tension member, a laterally projecting loop on one side of said tension member, and a laterally extending 30 cross-arm on the other side of said tension member; the units of the longitudinal rows having their proximate closed ends and loops 35 interlooped, and the units of the transverse rows having their proximate laterally projecting loops and cross-arms connected.

3. A wire link fabric made up of integral bent wire units arranged in longitudinal and transverse rows, each of said units comprising a two-ply tension member the two limbs 40 of which are joined at one end forming a closed end for the unit, a pair of loops at the other end of said tension member, a laterally projecting loop on one side of said tension member formed as an extension of 45 one of said loops, and a laterally extending cross-arm on the other side of said tension member formed as an extension of the other of said loops and terminating in a hook; the units of the longitudinal rows having 50 their proximate closed ends and loops interlooped, and the units of the transverse rows having their proximate laterally projecting loops and cross-arms interhooked.

4. A wire link fabric made up of integral 55 bent wire units arranged in longitudinal and transverse rows, each of said units comprising a two-ply tension member the two limbs of which lie closely adjacent to each other and are joined at one end by a U-bend, 60 a pair of closed loops at the other end of said tension member, a laterally projecting horizontally disposed loop on one side of said tension member formed as an extension of one of said closed loops, and a laterally 65 extending cross-arm on the other side of said

tension member formed as an extension of the other of said closed loops and terminating in a hook; the units of the longitudinal rows having their proximate U-bends and closed loops interlooped, and the units 70 of the transverse rows having their proximate laterally projecting loops and cross-arms interhooked.

5. A wire link fabric made up of integral bent wire units arranged in longitudinal and transverse rows, each of said units comprising a two-ply tension member the two limbs of which are joined at one end forming a closed end for the unit, a pair of closed 75 loops at the other end of said tension member, a laterally projecting loop on one side of said tension member formed as an extension of one of said closed loops, and a laterally extending cross-arm on the other side of said tension member formed as an extension of the other of said closed loops, said cross-arm at its inner end lying between the arms of said laterally projecting loop and terminating at its outer or free end in a hook, the units of the longitudinal rows having 80 their proximate closed ends and closed loops interlooped, and the units of the transverse rows having their proximate laterally projecting loops and cross-arms interhooked.

6. A wire link fabric made up of integral bent wire units arranged in longitudinal and transverse rows, each of said units comprising a two-ply tension member the two limbs of which are joined at one end forming a closed end for the unit, a pair of vertically 85 disposed closed loops at the other end of said tension member, a laterally projecting horizontally disposed loop on one side of said tension member formed as an extension of one of said closed loops and springing from 90 between the limbs of said tension member, and a laterally extending cross-arm on the other side of said tension member formed as an extension of the other one of said closed loops, said cross-arm also springing from 95 between the limbs of said tension member and between the arms of said laterally projecting loop and terminating at its outer or free end in a hook; the units of the longitudinal rows having their proximate closed 100 ends and closed loops interlooped, and the units of the transverse rows having their proximate laterally projecting loops and cross-arms interhooked.

7. A wire fabric made up of parallel rows 105 of tension units, each unit having a horizontal integral loop at one end and a vertical integral crossed-wire loop at the other end, the wire forming said vertical loop being continued from the rear end of that loop 110 cross-wise to the unit toward the next row of units for a cross-connection between adjacent rows.

8. As an article of manufacture, an integral bent wire unit having a two-ply ten- 115

sion member, the two limbs of which are joined together at one end and at the other end are provided with a pair of loops the sides of each of which intersect or cross each other, and a cross-arm formed as an extension of one of said loops.

9. As an article of manufacture, an integral bent wire unit, comprising a two-ply tension member the two limbs of which are joined at one end of said tension member, a pair of vertically disposed closed loops at the other end of said tension member, a laterally projecting horizontal loop on one side of said tension member formed as an extension of one of said closed loops and springing from between the limbs of said tension member, and a laterally extending cross-arm on the other side of said tension member formed as an extension of the other of said closed loops, said cross-arm also springing from between the limbs of said tension member and between the arms of said laterally projecting loop and terminating at its outer or free end in a hook.
10. A wire fabric made up of parallel longitudinal strands of interlooped bent wire units, each of said units having a two-ply tension member the limbs of which are integrally joined at one end of the unit, and a

two-ply loop at the other end of the unit, 30 the free end of the wire forming one ply of said loop being firmly secured to the tension member, and the wire forming the other ply of said loop being extended to form an integral cross arm for connection to an adjacent longitudinal strand. 35

11. As an article of manufacture, a wire fabric unit composed as to its body portion of double wires forming a pair of tension members integrally joined together at one 40 end, and at the other end being provided with a pair of terminal loops the sides of each of which intersect or cross each other, and an integral cross-arm formed as an extension of one of said terminal loops. 45

12. A wire fabric unit of that type having a body portion consisting of double wires joined together at one end of the unit, both wires being bent at the other end to form loops back of which loops each wire passes across itself, one wire forming a cross-arm and terminal hook and the other a lateral loop adapted to engage said terminal hook of an adjacent unit. 50

HENRY RICHARDSON.
